US0D1113804S

(12) **United States Design Patent** (10) **Patent No.:** **US D1,113,804 S**
(45) **Date of Patent:** **** Feb. 17, 2026**

(54) **HEADPHONE EAR CAP**

- (71) Applicant: **Dyson Technology Limited**, Malmesbury (GB)
- (72) Inventors: **Howard Shi-How Cheng**, Bristol (GB); **Philip Stephen Douglas**, Bristol (GB); **Damian Calvo Tome**, A Coruña (ES); **Chun Hei Poon**, Singapore (SG)
- (73) Assignee: **Dyson Technology Limited**, Malmesbury (GB)
- (**) Term: **15 Years**
- (21) Appl. No.: **29/954,713**
- (22) Filed: **Jul. 29, 2024**

(30) **Foreign Application Priority Data**

- Jan. 31, 2024 (GB) 6343519

CLAIM

The ornamental design for a headphone ear cap as shown and described.

DESCRIPTION

FIG. 1 is a front, top, right perspective view of a headphone ear cap showing our new design.

FIG. 2 is a front, bottom, left perspective view thereof.

FIG. 3 is a front, top, left perspective view thereof.

FIG. 4 is a front view thereof.

FIG. 5 is a rear view thereof.

FIG. 6 is a right side view thereof.

FIG. 7 is a left side view thereof.

FIG. 8 is a top view thereof.

FIG. 9 is a bottom view thereof.

FIG. 10 is a front, top, right perspective view of a headphone ear cap showing our new design.

FIG. 11 is a front, bottom, left perspective view thereof.

FIG. 12 is a front, top, left perspective view thereof.

FIG. 13 is a front view thereof.

FIG. 14 is a rear view thereof.

FIG. 15 is a right side view thereof.

FIG. 16 is a left side view thereof.

FIG. 17 is a top view thereof; and,

FIG. 18 is a bottom view thereof.

The broken lines show portions of the design that form no part of the claimed design.
